UNITED STATES PATENT OFFICE.

JOSEPH R. DUMONT, OF KANSAS CITY, MISSOURI.

DIRECTORY RACK.

Application filed March 3, 1922. Serial No. 540,717.

To all whom it may concern:

Be it known that I, JOSEPH R. DUMONT, a citizen of the United States, residing at Kansas City, in the county of Jackson and 5 State of Missouri, have invented certain new and useful Improvements in Directory Racks; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 This invention relates to directory racks especially designed for temporarily receiving cards and the like having certain indicia thereon.

The invention is particularly applicable 20 for use as a hotel rack in which guest cards may be removably attached to the rack in a convenient and expeditious manner although it is equally applicable for use as a rack for supporting information cards for general 25 business wherever credit cards, customers' list or other indicia-containing cards are used.

The primary object of the invention is to 30 provide an inexpensive, easily operated rack by means of which the cards may be temporarily secured in hanging positions so that both sides may be visible without removal from the rack and the construction is such 35 that the cards may be readily applied to or detached from the rack whenever desired.

The novel construction of the invention will be apparent by reference to the following description in connection with the accompanying drawings, in which

40 Fig. 1 is a perspective view of a rack constructed in accordance with my invention, parts being broken away to better illustrate other parts.

Fig. 2 is a longitudinal, sectional view 45 through a part of the rack.

Fig. 3 is a fragmentary, perspective view of part of the rack, showing the card-supporting bars ready to be removed.

50 Fig. 4 is a detail perspective view of one of the card-supporting bars, and

Fig. 5 is a top view of one of the card-supporting racks.

The rack frame is shown as consisting of 55 a back plate 1 having channel side rails 2 and 3, a top rail 4 and a bottom rail 5. Secured to the top rail 4 is a bowed spring 6

secured intermediate its ends and adapted to bear upon the top card bar, as will be clearly apparent by reference to Fig. 1.

The card bars are shown as comprising 60 angles 7, the rearwardly projecting lateral flanges 8 of which are of widths somewhat less than the depths of the channel members so the bars can slide therein.

The vertical flanges 9 of the card bars 65 are provided with end rearwardly projecting hook members 10 and 11 and intermediate hook members 12 and 13. There are two hook members 12 and 13 shown in Fig. 4 although the number may be multiplied if desired. The intermediate members are adapted to engage through slots 14 and 15 in the cards 16 and the overlapping end portions of the members 12 and 13 are slightly less in length than the width of the 70 members 10 and 11. In other words, the members 10 and 11 extend approximately the width of the flange 8 whereas the turned-over portions of the members 12 and 13 are not so long so that the cards can be introduced between the ends of 12 and 13 and the back plate 1.

The cards are readily adapted to be introduced over the hooked ends of the members 12 and 13 by inverting the cards, as shown 8 in Fig. 3, engaging their slots 14 and 15 upon said members and then turning them down, as shown in Figs. 1 and 2.

There is a card-bar supporting slide 17 in the channel members 2 and 3 and it is located below the lowermost bar 7. The support 17 consists of a plate having an upper longitudinal channel-shaped flange 18 and a lower outstanding flange 19, the widths of the flanges being enough to substantially fill 9 the channel members 2 and 3 so that the member 17 can readily slide therein.

The overlapping lip 20 of the flange 18 is adapted to engage over the upper edge 21 of a hinged plate 22, which is provided at 1 its lower end with a rod 23, extending the entire length thereof and having its ends resting in the channels 2 and 3 so as to constitute a hinge. The upper edge of the plate 22 is slightly notched, as at 24, so that the finger or an instrument can be inserted in the notch to pull the hinge plate outwardly when desired.

When it is desired to use the rack, the hinged plate may be swung down through 1 the medium of its hinge 23, then the member 17 will be slid to the bottom of the rack.

The card-supporting bars can then be introduced into the rack by inclining them diagonally so that their ends can engage in the channels. Then the bars can be straightened to lie horizontally, and when a sufficient number of the bars have been introduced into the rack, the member 17 can be slid up under the lowermost bar, and the plate 22 can be swung up so that the overlapping portion 20 of the flange 18 will engage over its edge. Therefore, the plate 17 will lock the swinging plate 22 in vertical position and the upper edge of the plate 22 will support the member 17 so that it, in turn, can support the adjacent bar 7.

If it is desired to introduce a card, the card is inverted and introduced between the lower edge of one bar and the upper edge of the other and since the hooked members 12 and 13 are relatively short, they can be caused to engage the slots 14 and 15. Then the card is swung over to a hanging position.

In causing the hooked members 12 and 13 of any bar to engage a card, the bar immediately above it can be raised so as to provide a space between the lower edge of the upper bar and the top edge of the bar to receive the card. This is due to the fact that the space between the upper edge of the member 17 and the ends of the spring 6 will not be entirely filled, there being slight play permitted. The cards can contain any indicia, such as the name and permanent address of a guest of the hotel, his ledger number, forwarding addresses and any other indicia which may be of interest.

Of course, the rack can be used for other purposes than a hotel register, so I do not wish to be limited to any particular application thereof, the invention residing rather in the inexpensive manner of constructing the same than in the use.

The gate or swinging plate 22 can be removed by tilting it so that the rod 23 will be inclined diagonally across the frame, whereupon the ends of the bar may be disengaged from the channels 2 and 3 and a larger plate 22 can be substituted.

When the bars are moved upwardly against the spring, the ends of the spring will bear against the ends 10 and 11, the spring constituting a buffer or shock-absorber.

What I claim and desire to secure by Letters-Patent is:

1. A device of the class described comprising a frame having side guides and a back, transverse card-carrying bars, each bar having ends engaging the guides and provided along its bottom edge with a horizontal flange, rearwardly projecting hooks intermediate the ends of each bar at the edge opposite to that at which the flange is located, the length of the hooks being less

than the depth of the guides and less than the width of the flange so that the free ends of the hooks will not contact with the back of the frame, the hooks constituting hangers for slotted cards, and rearwardly projecting members carried by each bar of greater length than the lengths of the rearwardly projecting hooks to maintain the rearwardly projecting hooks away from the back of the frame. 75

2. A device of the class described comprising a frame having vertical guides in its side edges, a spring at the upper end of the frame having depending free ends, card-carrying bars slidable in the guides, each comprising an angle member having a horizontal flange and a vertical flange, the vertical flanges being provided with overlapping members on their ends which are adapted to contact with the free ends of the springs, intermediate hook members, the intermediate hook members being of less length than the length of the end overlapping portions, and cards for engaging the intermediate hook members. 80 85 90

3. A device of the class described comprising a frame having side guides, vertically movable transverse card-carrying bars in the guides, a card bar supporting member in the guides beneath the lowest bar and adapted to have free vertical movement, and a hinged plate mounted in the frame and having an upper edge adapted to be engaged by the upper portion of the card bar supporting member whereby the card bar 100 supporting member will be held in elevated position.

4. A device of the class described comprising a rack having channel side guides, vertically movable transverse card-supporting bars in the guides, a bar-supporting member slidable in the guides and beneath the lowest bar, and a hinged plate carried by the guide for engaging the bar to hold it in elevated position, said hinged plate 110 having swinging movement away from the card-bar support whereby the card-bar support can be moved away from the lowermost card-supporting bar to permit the card-supporting bar to be tilted diagonally to remove it from the frame or to introduce it back into the frame. 115

5. In a device of the class described, a rack, card-supporting bars in the rack, each consisting of an angle member having a lateral flange and a vertical flange, end bent-over portions for the bar, and intermediate bent-over portions for the bar, the end bent-over portions being substantially as long as the width of the lateral flange and the intermediate bent-over portions being shorter than the width of the lateral flange. 120 125

6. A device of the class described comprising a rack, a plurality of vertically movable, transverse card-supporting bars in the 130

rack, a bar-supporting member slidable in the rack and beneath the lowermost bar, and means for maintaining the bar-supporting member in a raised position, said means comprising a hinged plate having its upper edge movable into and out of engagement with the bar-supporting member.

5 7. A device of the class described comprising a rack, a plurality of vertically movable, transverse card-supporting bars in the rack, a bar-supporting member slidable in the rack and beneath the lowermost bar, and

means for maintaining the bar-supporting member in a raised position, said means comprising a hinged plate having its upper edge movable into and out of engagement with the bar-supporting member, the bar-supporting member having an overlapping flange at its upper edge to engage the hinged plate to prevent the plate from accidentally swinging outwardly away therefrom.

15 20 In testimony whereof I affix my signature.
JOSEPH R. DUMONT.
